INCREMENTAL SANDING APPARATUS FOR
TRIMMING BOOK BLOCKS

Peter de Florez, Oyster Bay, and Francis J. Cashin, East Williston, N. Y., assignors, by
mesne assignments, to The De Florez Company, Inc., a corporation of Delaware

Application November 2, 1949, Serial No. 125,091

3 Claims. (Cl. 51—135)

1

The present invention relates to an apparatus for preparing the binding edge of a book page section or block and more particularly for removing the signature folds, or other folds, at the binding edge of a page section and imparting to the exposed edges of the page section a predetermined degree of smoothness or roughness. The invention is particularly adapted for use in the manufacture of hard cased books of high quality without sewing.

In that type of book binding which contemplates the use of a pliable adhesive coating as a binding means for a hard cased book it is necessary that a close bond be established between the binding adhesive and the edge of each individual page of the page block without exposing the page surfaces. To insure the bond between the page edges and the adhesive coating it is necessary to remove the signature or other folds at the binding edge and impart to the exposed page edges a surface texture which will make the strongest bond. In achieving this result it has been found that the heavy knife type of cutter, frequently used to trim the other edges of books, is not suitable for preparing the binding edge because the cut made by such a knife leaves a surface which is excessively smooth and glossy in character. Although a moderately smooth surface is desirable in certain cases, it is preferable in a cutting apparatus to have some provision for control of the smoothness of the cut. The heavy knife type of cutters or trimmers are incapable of adjustment or change to provide anything less than an extremely smooth cut. In addition, when such cutters of the guillotine type are employed the page block must be held stationary during the trimming operation and therefore such an apparatus is not suitable for inclusion in a continuous or assembly line type of process.

When metal cutters such as a rotary knife or band saw are utilized it is frequently necessary to increase or decrease the roughness of the surface with a sanding device in order to prepare the binding edge to accept a continuous smooth plastic surface for it is imperative that each page of the book presents an edge to the binding plane for binding. In using the various types of mechanical cutters it is necessary for efficient operation of the cutting tool to remove more paper than is required to reach all the pages in a signature type book page block in which there are a multiplicity of superimposed folds which must be cut through. If the cut is not sufficiently deep the cutting tool will be deflected and will pass under the book block, or at least under some of the pages thereof.

The method and apparatus of this invention obviates the use of mechanical cutters and provides a series of continuously moving abrading surfaces which incrementally trim the binding

2

edge as the page block is moved continuously into contact with the abrading surfaces positioned at successive stations along the path of the page block.

5 An important object of the invention is to provide an efficient and simple means for preparing the binding edge surface of the page block or section to a predetermined degree of roughness, such means being adjustable to vary the roughness of the binding surface.

10 Another object is to provide an apparatus wherein only the minimum amount of paper, necessary to expose each page in the binding edge, is cut from the page block, with a consequent saving in paper.

15 A further object is to provide an edge trimmer which is capable of inclusion in a continuous process system of book manufacture.

An additional object is to provide an apparatus 20 in which the folds of paper may be removed in several increments reducing the excessive pressure against the moving page block and thereby enabling the page blocks to be conveyed and processed at greater speeds and without burning 25 the paper.

The invention may be more fully described by reference to the drawings, in which:

Fig. 1 is a schematic plan view illustrating one embodiment of the invention;

Fig. 2 is a side elevational view of the abrading apparatus as viewed from line 2—2 in Fig. 1;

Fig. 3 is a plan view of a single abrading device;

Fig. 4 is a side elevation of the abrader with the removable guide plate removed;

Fig. 5 is a vertical section taken along the line 5—5 in Fig. 3;

Fig. 6 is a detail, chiefly in horizontal section, of the removable guide plate of the abrader;

Fig. 7 is a vertical section on line 7—7 of Fig.

40 6, and

Fig. 8 is an enlarged end view of a page block before and after processing.

The apparatus embodying the invention illustrated in the drawings includes a series of abrading stations disposed in the path of continuously moving book page blocks and arranged to perform prescribed operations as each succeeding page block is presented. The operations will be fully set out hereinbelow.

Referring to Figs. 3, 4 and 5, each abrading station 10 has a supporting frame 25, an abrading belt 26, made of any suitable material such as sand paper or emery cloth, mounted on rotatable cylinders 27, 28. The abrading belt 26 is driven by friction contact with the driven cylinder 27 to which power is transmitted by a belt and pulley system 43 shown in part in Figs. 1 and 3.

The idler cylinder 28 is rotatably journaled in an arm 30 which is pivotally mounted to the frame 25 by pivot pin 11 passed through stud 12. Tension spring 29 is connected to the arm 30 and to

the bracket 31, affixed to the supporting frame 25, and is arranged to draw the cylinder 28 away from the driven cylinder 27 and thereby maintain the belt 26, which is mounted on the cylinders, under sufficient tension to insure frictional contact with the driven cylinder 27. The amount of tension of spring 29 may be changed by adjustment of wing nut 21 which is threaded on spring post 22.

Guide plates 32, 33 are supported by the frame 25 in a horizontal position slightly above the face of the abrading belt 26. The guide plates lie in the same plane and their faces are parallel and separated to permit the passage of a book block therebetween. The space between the guide plates 32, 33 defines a diagonal path across the face of the abrading belt. Vertically adjustable platen 34 is positioned beneath the abrading belt 26 to give support to the belt during the abrading operation, and to adjust the horizon of the abrading surface.

Although useful in other circumstances, the apparatus of this invention is of particular advantage when it is employed in conjunction with book manufacturing operations of a continuous type such as those disclosed in the co-pending application filed May 1, 1948, Serial No. 24,494, of Luis deFlorez, Peter deFlorez, and Owen L. Gore.

The page blocks, which it is contemplated to process in the present apparatus, may be composed of either the folded signatures of the type shown in Fig. 8, which have been used generally in making hard case books wherein a multiplicity of superimposed folds 46 of paper are presented at the binding edge, or they may be made up of an accordion folded web of paper, in which only single folds are in the binding edge of the page block. When the page blocks are composed of folded signatures the amount of paper which must be trimmed from the binding edge by the several abrading stations must be sufficient to cut through the several superimposed folds of paper, to thereby expose the edge 44 of each leaf 43 of the page block in the finished binding edge surface 45 shown in Fig. 8. Referring to Figs. 1 and 2, the page sections or blocks 18 are positioned in the clamps 19 of a continuous conveyor (not shown) so that the binding edges to be cut occupy a common horizontal plane *a* in Fig. 8. The abrading belts 26 of each successive abrading station 10 are adjustable vertically to intercept the common plane through which the uncut binding edges are conveyed at several incremental levels, i. e. levels *b*, *c*, and *d*, shown in Fig. 8.

The economy of paper and of cutting energy which can be effected by use of this invention may be appreciated by comparing the final incremental abrasion level *d* with line *e* which is the level at which the various types of knife-cutters operate so that the cutting tool is not deflected and passed under the binding edge. With the knife-cutters it is also necessary to remove additional paper, i. e., above line *e*, to obtain the desired roughness of surface texture.

The adjustments for a predetermined amount of abrading at the binding edge also may be accomplished by changing the horizontal plane through which the binding edges move.

Each successive page block is conveyed into engagement with the abrading stations positioned along the predetermined path which the page blocks travel. The successive abrading stations 10 are spaced apart along the predetermined path of travel of the page blocks and are positioned so

that the rapidly moving abrading surfaces contact the binding edges of the page blocks in a horizontal plane. In the area of contact with the binding edges the abrading surfaces are moving in the opposite direction to the travel of page blocks, as indicated by the arrows in Figs. 1 and 2, and the several abrading stations are angularly disposed to the path of the continuously conveyed page blocks, as shown in Fig. 1, so that the several abrading surfaces move diagonally across the binding edges during the successive abrading operations. An angle of from 5° to 15° to the line of travel of the page blocks has been found suitable to effect more efficient cutting and to permit the relief or unloading of the paper dust during the abrading operation.

In order to increase or decrease the frictional contact between the abrading surfaces 26 and the binding edges of the successive book blocks, the platen 34 is mounted for vertical adjustment on the threaded shaft 36 which in turn is mounted in the collar 37, attached to supporting frame 25. The knob 35 is provided at the end of shaft 36 so that the latter may be turned up or down in the collar 37. After passing over the last abrading surface, which imparts the final degree of roughness or smoothness to the binding edge, the page block moves forward to receive the adhesive coating and to be further processed in accordance with the process contemplated in the co-pending application of Luis deFlorez, Peter deFlorez and Owen L. Gore, filed May 1, 1948, Serial No. 24,494.

The guide plates 32 and 33 in the abrading station are arranged so as to engage the outer leaves of each successive page block, slightly above the binding edge which is to be abraded, and press the leaves and folds of the binding edge together under yielding pressure. The page block engaging faces 13 and 14 of the guide plates flare outwardly at the receiving end of the abrading station to gather the outer leaves of the page block into the restricted slideway defined by the guide plates. The guide plates receive the page block before it is subjected to the sanding or abrading operations and hold the binding edge, thereby preventing the individual page ends or edges from being fanned outward by the motion of the abrading belt 26. When the outer pages are not held properly and are permitted to fan, an uneven edge results, having torn and ragged edges of the leaves near the outer faces of the page block. The most desirable finished texture for the binding edge is one in which the individual page edges have a uniform degree of roughness and lie in a common plane.

In order to accommodate book page blocks of varying widths the outer guide 32 is laterally adjustable by means of threaded stops 38 and spring pressure adjustments 39, all of which traverse a flange 15 which depends from the guide 32 and which supports the latter, as shown in Figs. 5 and 7. The threaded stops 38, engaging the bar 40, establish the inner limit of the guide plate 32. Shafts 11 are mounted in the bar 40 by screw connections 48 and extend outwardly as shown in Figs. 6 and 7.

The flange 15 of the guide plate 32 is slidably mounted on the shafts 11 and is pressed yielding inward along the shafts by the coil springs 16 surrounding the shafts and abutting the outer face of the flange 15. The spring pressure may be varied by adjusting spring pressure adjusting wing nuts 39 threaded on the shafts 11, which abut the other end of the springs 16. The slide mounting of the guide plate flange 15 permits

the guide plate 32 to be laterally displaced in an outward direction against the yielding pressure of springs 16. The outer guide 32 may thus be given a set adjustment and at the same time be removed to allow easy access to the abrading belt for rapid replacement thereof.

The outer guide 32 can be removed by lifting the bar 40 (see Figs. 5 and 7) out of the slots 42 in the bracket 41, the latter being permanently fastened to the frame 25. The guide bar 33 in the present form of the invention is fixed to the frame by screws 20. However, it will be appreciated that a suitable adjustable and resilient mounting could be provided for it similar to the mounting for guide plate 32.

Although it might seem desirable to proceed with the relatively rough surface resulting from a single abrasive pass, i. e. as furnishing more "tooth" for the subsequently applied adhesive, experience indicates that the roughness is occasioned by relatively loose fibers which may become embedded in the adhesive but have no holding strength relative to the leaves of the page block. With a relatively smooth edge there is little looseness of the fibers and much better opportunity for penetration of the adhesive edge-wise into the individual leaves for maximum holding effect.

The optimum degree of smoothness or roughness depends upon the character of the paper and an advantage of this combination of sanding incrementally is that a variable and controllable surface texture may be produced. With relatively non-absorptive papers a binding surface of only moderate smoothness is satisfactory and may often be most desirable to secure the optimum endwise bond with the adhesive coating. With many papers of high or considerable absorptiveness, however, an extremely smooth surface is preferred. Another factor which will enter into a determination of the smoothness desired is the type of adhesive to be used including its penetrating and bonding qualities.

The coarseness of the several abrading sanding surfaces may be varied to produce a binding surface, i. e., the final surface of the binding edge of the book block, of predetermined smoothness. Minor variations in the binding surface texture may also be achieved by a change in speed of the abrading belt and by vertical adjustment of the platen 34 to increase or decrease the pressure contact of the sanding belt with the binding surface.

The incremental sanding method and apparatus of the invention is of particular advantage as a manufacturing procedure because the incremental nature of the operation performed by the several individual abrading surfaces enables each to last longer in operation and avoids frequent renewals. Furthermore, the action of each abrader is more uniform for a considerable period of operation as it is not worn down as rapidly or as extensively as would be the case if the entire operation were attempted with the use of a single sander.

Although the use of belt sanders or abrading surfaces are presently preferred, rotary disc and peripheral sanders also may be used.

It will thus be appreciated that the present invention, by controlled adjustments of the successive incremental abrading operations, produces binding surfaces of a predetermined degree of smoothness or roughness on successive page block units and that the invention may be embodied readily in a system of book manufac-

ture wherein successive page blocks are conveyed along a predetermined path and subjected to the various processes and forming operations at work stations disposed along the path. It will be noted also that with this invention no more paper is removed than is necessary to expose all the pages in the binding edge and to impart the desired surface texture.

In accordance with the patent statutes, the best mode known of carrying out the principles of the invention has been described in this specification, but it will be understood that the structures disclosed are only illustrative and the invention may be carried out by other means. Also, while it is contemplated that the various arrangements and elements be used in the combinations and relations described, some of these may be altered and modified in ways, other than those suggested, without departing from the spirit and scope of the invention.

What is claimed is:

1. In an apparatus for trimming the binding edges of books, more than one abrading station, a book conveyor adapted to hold firmly a book page block to be trimmed and to convey it and to present the binding edge successively to sanding surfaces in said abrading stations, said abrading stations being spaced apart and each station having a sanding surface, supporting and driving means for said sanding surface adapted to drive said sanding surface and to maintain it in horizontal abrading contact with said binding edge, said sanding surface of each station being arranged to cut and abrade the edge of the book page block diagonally to the path of travel of said book page block, supporting guides disposed at the abrading station adjacent and just out of contact with said sanding surface and spring means for resiliently pressing the guides against the face of each passing page block adapted to slidably engage the sides of the page blocks adjacent the binding edges and to guide the book page blocks during their passage over the sanding surface, and for maintaining the leaves of the page block against lateral displacement by said sanding surface.

2. The apparatus of claim 1 which includes means for removably mounting said supporting guides, said means being adjustable for varying the spacing of said guides.

3. The apparatus of claim 1 which includes means for removably mounting said supporting guides, said means being adjustable to vary the spacing of the guides, at least one of said guides being adapted for yieldable lateral displacement.

PETER DE FLOREZ.
FRANCIS J. CASHIN.
